TURBINE ROTOR BLADE

Morton I. Weinberg, Ypsilanti, Mich., assignor to
 Packard Motor Car Company, Detroit, Mich., a
 corporation of Michigan

Application October 11, 1948, Serial No. 53,846

1 Claim. (Cl. 253—77)

1 The invention relates generally to turbine rotor constructions and more particularly to blade structure for gas turbines.

The general object of the invention is to provide a rotor for a gas turbine, having blades which are capable of operating without danger of breakage due to the high operating speeds and the high temperature of the gases.

More specifically, it is an object to provide a novel blade structure in which undesired stresses are eliminated or at least minimized so that the blade can, without breakage, withstand the operating conditions to which it is subjected.

Another object is to provide a novel blade structure facilitating manufacture at a reasonable cost.

A further object is to provide a novel blade for a gas turbine, in which the structure providing for elimination and minimization of undesired stress results in a shape which is hollow and facilitates the passage of cooling air therethrough.

Other objects and advantages will become apparent from the following description taken in connection with the accompanying drawings, in which:

Figure 1 is an axial sectional view of a turbine rotor embodying the features of the invention and showing one of the blades thereof partially in elevation.

Fig. 2 is an enlarged view of the outer end of one of the blades employed in the rotor shown in Fig. 1.

Fig. 3 is a sectional view taken on the line 3—3 of Fig. 1.

Fig. 4 is a sectional view taken on the line 4—4 of Fig. 1.

Fig. 5 is a sectional view taken substantially on the line 5—5 of Fig. 1.

In constructing a turbine rotor for a gas turbine, difficulties are encountered by the designer of such a rotor because of the high speeds at which such rotors operate and because of the high temperatures to which the blades thereof are subjected. The temperature of the metal in the blades, of course, may be held materially lower than that of the gases by making the blades hollow and conducting a stream of cooling fluid, such as air, through each blade. Even with such an arrangement, the temperature of the blade becomes fairly high so that the strength of the metal is substantially reduced from that obtainable at lower temperatures. This fact, coupled with the excessive speeds at which the blades operate, renders the design of such blades difficult.

2 The stresses occurring in each blade are due not only to the centrifugal forces involved, but also to the torsional effects on the blade due to the force of the gases acting on the blade and the relative location of the cross-sectional center of gravity. In fact, these stresses may be more critical or more difficult to meet than the stresses due to the centrifugal action. With a hollow blade having a rather thin wall, another form of stress occurs, particularly at the tip or outer end of the blade. Thus, unless the blade is properly designed, the portions of the two side walls of the blade intermediate the front and rear edges may flex relative to each other at the tip of the blade to cause what may be termed a "breathing" action. This, of course, sets up stresses on the metal which are superimposed on the stresses heretofore mentioned.

A turbine blade of the character herein contemplated may be likened to a highly cambered airfoil in which the maximum spar depth is found well forward in the blade, so that principles of design of an airfoil may be applied thereto. In applying such principles, the blade in any transverse section may be said to have a neutral axis, at any given cross section, about which the compression and tension forces are balanced when the blade tends to bend as it is loaded and a shear center for any given neutral axis, which is defined as the point at which a load applied normal to that axis will produce no torsion in the section. The load in the present instance, of course, is a component of the force applied by combustion gases driving the turbine. To prevent any torsional effects upon the blade, the center of gravity for such transverse section should substantially coincide with the shear center. With such an arrangement, the stresses due to the torsional effects will be eliminated.

The breathing action of the side walls of the blade at the tip can be substantially eliminated by rigidly tying them together, preferably throughout the radial length of the blade, the tie being provided preferably at or adjacent the point of maximum breathing. Such attachment between the two walls at that point is provided by a portion in the nature of a web which obviously necessitates the use of material affecting the location of the center of gravity in any transverse section.

The present invention contemplates a blade embodying the foregoing principles, and in Figs. 3, 4 and 5 of the drawing there are shown transverse sectional views of the blade at varying radial distances from the axis of rotation of the rotor.

In Fig. 5, which is a transverse sectional view of the blade intermediate its ends, I have shown what may be termed a typical section, to illustrate the foregoing principles. Thus, dash-and-dot line 10 in Fig. 5 may be said to be the neutral axis of the section of the blade illustrated therein. The point 11 indicates the shear center of this section, which, by definition, is the point about which the load applied normal to the axis 10 will produce no torsion in the section. The distribution of metal in the section is such that the center of gravity for the section lies substantially at the point 11. Thus, there will be no torsional effect acting on the blade, about the point 11, to produce undesired stresses in the blade.

The section shown in Fig. 5 also illustrates the manner in which stresses due to the breathing action of the side walls of the blade are eliminated. Thus, it will be noted, the blade comprises a pair of spaced side walls 12 and 13. These walls are interconnected at the front and rear edges of the blade but will undergo a breathing action relative to each other, particularly at the tip of the blade, unless they are rigidly tied together intermediate the front and rear edges. For this purpose, an intermediate rib 14 is provided, which is illustrated as being integral with the wall 12 and is welded to the wall 13. The rib 14 extends throughout the radial length of the blade so that the two walls 12 and 13 are thus held in fixed relation to each other, not only at the front and rear edges of the blade but intermediate such edges. By this means, substantially no breathing action between the walls takes place, and the stresses occurring because of any breathing action are thereby eliminated.

A blade having the foregoing characteristics may be readily manufactured in what may be termed a two-part construction. One of such parts, which may be termed the body member, comprises the wall 12 with the rib 14 integrally formed therewith. A rib or ridge 15 may also be formed integrally with the wall 12 at the front edge of the blade, while a similar rib 16 may be formed at the rear edge of the wall 12. The outer or tip end of this part has an end wall portion 17, while the inner end is provided with a wall portion 18. This one part comprising the wall 12 and the ribs may be readily formed either by a casting process or a forging process, either of which may be broadly defined as "hot forming." The wall 12 in the present instance constitutes, as will be obvious, the low-pressure or rear face of the blade.

The opposite or high-pressure face of the blade, formed by the wall 13, is provided by the other part of the two-part construction and, in the present instance, comprises a camber plate 13 made of sheet metal. The camber plate 13 thus may be punched from a sheet and is then curved to fit against the ribs 14, 15 and 16 and bridges the spaces therebetween. To rigidly secure the camber plate to the ribs and make it an integral part thereof, the ribs and camber plate are welded together throughout their area of contact. The camber plate is also welded at its ends to the wall portions 17 and 18. After such welding, the front and rear edges of the plate 13 may be rounded to conform to the desired rounding of the edges of the ribs 15 and 16. The welding of the plate 13 to the intermediate rib 14, as heretofore mentioned, ties the two walls 12 and 13 together to prevent the breathing action.

The particular form of the ribs 14, 15 and 16 in their relation to the walls 12 and 13 provides a center of gravity for any transverse section, such as illustrated in Fig. 5, which is located at the shear center for such section. Stresses due to torsional effects are thereby substantially eliminated, so that the centrifugal stresses are the only ones which, with this construction, remain of material magnitude. Provision for such centrifugal stresses, however, may be made by increasing the strength of the blade toward its inner end. Thus, as is noted by a comparison of Figs. 3, 4 and 5, the ribs 14, 15 and 16 are of greater depth near the inner end of each blade than at the outer end, providing a blade of tapering thickness. The thickness of the wall 12 is also increased toward the inner end of the blade so that the centrifugal stresses can well be sustained without danger of breakage of the blade. The camber plate 13, since it is made from sheet metal, is preferably of uniform thickness throughout its radial length.

In Figs. 1, 2 and 3, the manner in which the blade is attached to a rotor has been indicated. Thus, the wall portion 18 of the blade is formed on a base 20 of generally rectangular shape. The base 20 is provided with a plurality of spaced tangs 21 adapted to interfit with similar tangs 22 formed on the periphery of the rotor of the turbine, indicated at 23. The two outer tangs on the base 20, indicated at 24 (see Figs. 1 and 3) are preferably segmental in form and of such size that they abut the corresponding tangs of the adjacent blades. The base 20 is also of such size that it abuts the bases of adjoining blades, so that the bases 20 and tangs 24 provide a complete rim about the rotor 23. The tangs 21 and 24 on the base 20 are secured to the tangs 22 on the rotor 23 by means of a pin 25 extending therethrough, as illustrated in Fig. 1.

It is contemplated, of course, that with a hollow construction for the blade, cooling air will be passed through the blade to keep the metal of the blade at sufficiently low operating temperature. The rotor 23, in the present instance, is provided with an air-receiving chamber 30 in its central or hub portion, from which extend a plurality of radial air passages 31. In the present instance, the passages 31 are in a staggered relation to each other to provide a sufficient number of such passages without weakening the rotor. The passages 31 extend outwardly to discharge air against and between the tangs 21 and 22. The tangs 21, as will be noted in Fig. 3, are of less peripheral width than the base 20, so that there is space for the air to circulate about the tangs.

The rib 14 extending throughout the length of the blade proper divides the interior of the blade into two passages, indicated at 32 and 33 in Fig. 3. These passages are adapted to receive the air, which circulates about the tangs, by means of a pair of apertures 34 (see Fig. 3) bored through the base 20 and each generally aligned with one of the spaces between a pair of tangs 21. The tangs 22 on the rotor 23 are of less radial depth than such space, so that air is free to circulate over the outer end of the tangs 22 and pass outwardly through the apertures 34 into the respective passages 32 and 33. The air then passes outwardly through the blade and is discharged or vented at the outer end thereof through a pair of notches 35 cut in the outer end of the camber plate 13. By the separation of the interior of the blade into the two separate passages 32 and

33, a definite flow of air is provided, both in the front edge portion of the blade and in the rear edge portion, so that the edge portions of the blade formed by the ribs 15 and 16 will be adequately cooled.

It has been noted that, in gas turbines, the hot combustion gases have an abrading effect on the metal of the blades, such effect being concentrated chiefly at the leading or front edge of the blade. With the present construction, the rib or ridge 15 provides a heavy wall section at the point of great abrasion, so that the structure will not be materially weakened by the abrasion.

I claim:

A hollow turbine blade having the form of a highly cambered twisted air foil of varying cross-section in which the maximum spar depth is well forward in the blade, said blade having a rear wall and a forward wall, a thickened leading edge and a relatively thin trailing edge, a longitudinally continuous generally centrally disposed stiffening rib integrally formed with said rear wall and engaging said forward wall, each of said cross sections having a neutral axis, a shear cen-

10 ter located at a point along said axis, and the mass of said blade and rib being so disposed that the center of gravity of any such cross section is located in said axis at said shear center where-

5 by substantially no torsional effects are produced upon the blade and the stresses inherent in such effects are thus substantially eliminated.
